UNITED STATES PATENT OFFICE.

JOHN H. MORGAN, OF CHICAGO, ILLINOIS.

THROW-RAIL FOR COMBINED THIRD AND TRACTION RAIL SWITCHING SYSTEMS.

SPECIFICATION forming part of Letters Patent No. 772,735, dated October 18, 1904.

Application filed April 16, 1904. Serial No. 203,466. (No model.)

To all whom it may concern:

Be it known that I, JOHN H. MORGAN, a citizen of the United States, residing at Chicago, in the county of Cook and State of Illinois, have invented a new and useful Improvement 5 in Throw-Rails for Combined Third and Traction Rail Switching Systems, of which the following is a specification.

This invention relates to throw-rails for 10 combined third and traction rail switching systems.

The object of the invention is to provide a 15 construction of throw-rail for combined third and traction rail systems which is simple in construction and efficient in operation and whereby the truck may be switched from one track to another and the traction-gear carried by the truck maintained in efficient 20 conducting and traction engagement with the traction-rack during the switching movements.

Other objects of the invention will appear more fully hereinafter.

The invention consists, substantially, in the 25 construction, combination, location, and arrangement of parts, all as will be more fully hereinafter set forth, as shown in the accompanying drawings, and finally pointed out in the appended claims.

30 Referring to the accompanying drawings, and to the various views and reference-signs appearing thereon, Figure 1 is a view in plan, somewhat diagrammatic, showing a form of throw-rail embodying the principles of my invention as applied to a main track and a single switch therefrom. Fig. 2 is a similar view showing the application of a form of throw-rail embodying my invention as applied to a three-way switching system. Fig. 3 is a 35 view in top plan of a form of throw-rail detached and embodying the principles of my invention. Fig. 4 is a detail view, in transverse section, on the line 4-4, Fig. 3, looking in the direction of the arrows.

40 The same part is designated by the same reference-sign wherever it occurs throughout the several views.

45 In the operation of a combined third and traction rack rail haulage system wherein the 50 rack-rail performs the double function of a

conductor and a traction-rack and in order to permit of the use of such a rack-rail and especially at the junction of a branch or connecting line or a crossover it is desirable to make provision for a constant engagement of 55 the driving-gear on the truck with the combined third and traction rack while passing over the switch or from one track to another. Usually a fixed traction-rack is employed for each pair of track-rails, whether such 60 track-rails are the main track-rails or track-rails of a branch or switch therefrom, and in order to secure the continuity of the combined conductor at the switch or turnout it has been proposed in Patent No. 753,802, is 65 issued March 1, 1904, to E. C. Morgan, to employ a combined third and traction rack made in sections, whereby such sections may be be shifted into and out of proper position to constitute continuity of the traction-rack. In 70 this instance, however, a pivoted section of traction-rack is provided for each pair of track-rails, the pivoted section for the main track-rails being shifted out of operative relation and the pivoted section of the switch- 75 ing track-rack being shifted into operating relation when the truck is to proceed from the main track to the switch track, and vice versa. The present invention relates to de- 80 vices of this nature and resides particularly in the construction of throw-rails employed to secure continuity of traction-rack, the ob- 85 ject being to combine in a single pivoted section a structure serving to effect continuity of traction-rack for the main track-rack as well as for one or more branch track-racks.

Referring to the accompanying drawings, reference-sign A designates main track-rails, and B and C switching track-rails. In Fig. 1 I have shown only one pair of switching 90 track-rails B, while in Fig. 2 I have shown two pairs of switching track-rails B, one pair being designated by reference-sign B and the other by reference-sign C, as illustrating the mode of application of my invention. Asso- 95 ciated with the main track-rails A is a com- 100 bined third and traction rack D, and associated with the switch track-rails B is a com- bined third and traction rack E, and associated with the switch track-rails C is a combined

third and traction rack F. Where a switch or turnout occurs, however, a gap is provided between the proximate ends of adjacent portions of the traction-rack D of the main track-rails, so as to enable a truck to pass from the main track-rails to the switch track-rails and along the latter without interference from the traction-rack, and, similarly, the branch or switch track-sections E F of the traction-rack terminate outside of the main track-rails A for the same purpose—namely, to permit the truck-wheels to pass along the main track-rails A without interference from the traction-rack of the switch-tracks.

15 In accordance with the principles of my invention I propose to employ a single pivoted section of combined third and traction rack and to provide the same with one or more rows of engaging rack-teeth for the 20 traction-gear on the truck or locomotive, according to the number of turnouts or switches with which such pivoted section is associated, so as to enable the same or a single pivoted section of combined third and traction rack 25 to be thrown into position to afford continuity of traction-rack for any one or more main and switch tracks. This pivoted section of combined third and traction rack is indicated generally in Fig. 1 by reference-sign G and 30 in Fig. 2 by reference-sign G', said sections being pivoted, as at H, adjacent to the end of one of the main-track-rack portions D, and I provide this pivoted section with two or more rows of perforations or teeth for coöperative engagement with the teeth of the 35 traction-gears, according to the number of switch-tracks, one of such rows of perforations or teeth coöperating with the traction-rack of the main track and others adapted to 40 be brought into coöperative relation with respect to the traction-racks of the switch-tracks. Inasmuch as the switch-tracks are ordinarily curved to form the turnout from the main tracks, it becomes necessary to form 45 the line of perforations or rack-teeth of the pivoted section of traction-rack to the curvature of the switch-tracks. Therefore where one pair of switch-tracks only is provided, as 50 shown in Fig. 1, I provide the pivoted section G of the combined third and traction rack with two rows of teeth or perforations, one being a straight row, as indicated at J, adapted to be brought into alignment with the main-track-rack portions D and the other 55 line of perforations or rack-teeth (indicated at K) being on a curve corresponding to the curvature of the switch track-rails B, and, similarly, where two switch-tracks B C are employed, as in Fig. 2, the combined third 60 and traction rack section G' is provided with three lines of perforations or teeth, the one or central line (indicated at J) being a straight line or row and adapted to be brought into alignment with the sections D of the main 65 track when it is desired that the truck or

locomotive shall proceed along the main track-rails. The section G' is also provided with the curved line of perforations or rack-teeth K, corresponding to the curvature of the switching track-rails B and adapted to be 70 brought into register with respect to the traction-section E of such switching track-rails B when it is desired that the truck shall proceed from the main track - rails A to the switching track-rails B, and, similarly, the 75 pivoted section G' is provided with the curved line of perforations or rack-teeth (indicated at L) adapted to be brought into register with the traction - rack F of the switch-track C when it is desired that the locomotive or 80 truck shall proceed along such switching track-rails, as indicated in the dotted-line positions.

In Figs. 3 and 4 I have shown a specific 85 construction of the pivoted section and embodying the principles of my invention wherein the traction-rack proper comprises a plate (indicated at M) the ends of which are received in grooves or seats formed to receive the same in insulating-stringers N, the edges 90 of the rack-plate M being secured in the seats in the opposed faces of stringers N in any suitable or convenient manner—as, for instance, by the securing devices indicated at O, Fig. 4. The plate M is perforated, as 95 indicated, to impart thereto the character of the rack, as indicated at J, K, and L. If desired, insulating-strips P may be secured in any convenient manner—as, for instance, by means of securing devices Q—to the rack-plate between the rows or lines of perforations or rack-teeth formed in such plate and so as to efficiently protect against accidental contact with such rack when it is employed 100 as a conductor. Instead of the lines or rows 105 of perforations J K L extending the entire length of the pivoted section of traction-rack said lines or rows extend for only a portion of the length of such section, such section being provided at each end of the lines or 110 rows of perforations J K L with slots or teeth (indicated at R) of decreasing length transversely of the rack toward the extreme end of such rack and which enlarged slots or 115 openings permit of the engagement therewith of the traction-gears of the truck as such gears initially advance along such rack, thereby permitting the switch-points S of the switch-tracks to direct the locomotive or truck along the desired switch-track from 120 the main track before the traction-gears reach the particular line of rack - teeth J, K, or L corresponding with the particular track along which the locomotive or truck is to progress. In this manner the enlarged transverse slots or openings or teeth R coöperate 125 with each of the lines or rows of rack-teeth or perforations, and in case of a three-way throw-rail, as shown in Figs. 2 and 3, I provide the rack-section, at the extreme free end 130

thereof, with the transverse line of openings or teeth A' B' C', each corresponding in area of opening to the area of opening of the teeth in each of the track rack-sections D E F, the 5 opening B' adapted to form the first pivoted section-opening in coöperation with switch track-rack D, A' forming the first pivoted section to coöperate with switch track-rack E, and C' forming the first pivoted section- 10 opening coöperating with switch track-rack F. Immediately following the transverse row of rack-openings A' B' C', at the extreme free end thereof, such rack-section is provided with a series of transverse slots or openings 15 D' of decreasing length transversely of the track-rack before the series of transverse slots or openings R are reached, counting from right to left in Fig. 2, the series D' tapering to meet the taper of the series R of 20 the openings until finally a single slot or opening E' is attained which is of standard width or area. If desired and in order to efficiently insulate the three-way throw-rail constructed as above described at the point where the series 25 R and D' occur, flanking pieces of insulating material, such as wood, F' may be employed. (See Fig. 3.)

From the foregoing description it will be observed that I provide an exceedingly simple 30 throw-rail which is efficiently insulated and wherein efficient protection is afforded against accidental contact and wherein in a single throw-rail provision is made for effecting continuity of traction-rack along a main track or 35 one or more branch or switch tracks and wherein the lines of rack-teeth in the throw-rail conform to the curvature of or path traversed by the truck when proceeding along the switch-tracks.

40 Having now set forth the object and nature of my invention and various forms of construction embodying the principles thereof, what I claim as new and useful and of my own invention, and desire to secure by Letters Patent, is—

1. A throw-rail for combined third and traction rack rail switching systems having a plurality of rows or lines of perforations or rack-teeth, as and for the purpose set forth. 50 2. The combination with main and switch track-rails and traction-racks for each pair of rails, of a throw-rail section of traction-rack having a plurality of rows or lines of perforations or rack-teeth, each line or row of such 55 perforations or teeth adapted to be brought into register with the traction-rack of a corresponding switch-track to effect continuity thereof, as and for the purpose set forth.

3. The combination with main or switch 60 track-rails, and a traction-rack for each pair of rails, of a single throw-rail having lines or rows of rack-teeth or openings, each adapted to be brought into register with the traction-rack of a corresponding pair of rails, as and 65 for the purpose set forth.

4. The combination with main or switch track-rails, and a traction-rack for each pair of such rails, of a single throw-rail having lines or rows of rack-teeth or openings, each adapted to be brought into register with the 70 traction-rack of a corresponding pair of rails, the lines of perforations or teeth corresponding to the traction-rack of a switch-track being curved to conform to the curvature of the switch-track rails, as and for the purpose set 75 forth.

5. The combination with main and switch track-rails, and a traction-rack for each pair of rails, said traction-racks having gaps therein at the switch or turnout, of a single throw-rail pivotally connected at one end and having a plurality of lines or rows of openings or perforations forming rack-teeth, each adapted to be brought into registering relation at the free end of such throw-rail with a corresponding 80 traction-rack portion of the main switch-tracks, as and for the purpose set forth.

6. A throw-rail for combined third and traction rack rail switching systems, comprising a plate having perforations forming rack-teeth formed therein and arranged in independent rows or lines lengthwise of such plate, as and for the purpose set forth.

7. A throw-rail for combined third and traction rack rail switching systems, comprising a plate having perforations or openings therethrough arranged in lines, and insulating-stringers between which said plate is received, as and for the purpose set forth.

8. A throw-rail for combined third and traction rack rail switching systems, comprising a plate having rows of perforations or openings therethrough, in combination with stringers having seats or grooves formed in the opposed edges thereof to receive the edges 100 of such plate, and means for securing such plate in said stringers, as and for the purpose set forth.

9. A throw-rail for combined third and traction rack rail switching systems, comprising a plate having rows of perforations or openings therethrough, insulating-stringers between which said plate is secured, and insulating-strips carried by said plate between adjacent rows of perforations, as and for the 110 purpose set forth.

10. A throw-rail for combined third and traction rack rail switching systems, comprising a plate having openings or perforations therethrough arranged in lines extending lengthwise of such plate, and a series of transverse slots or openings at the ends of such 120 rows of perforations, said transverse slots or openings being of decreasing length transverse of such plate toward the ends of such 125 plate, as and for the purpose set forth.

11. A throw-rail for combined third and traction rack rail switching systems, comprising a plate having openings or perforations therethrough and arranged in lines ex- 130

tending lengthwise of such plate, one of such rows being a straight row and the others being curved, as and for the purpose set forth.

12. A throw-rail for combined third and traction rack rail switching systems, comprising a plate having rows of perforations or openings extending lengthwise thereof, said plate having a transverse row of perforations or openings at one of the extreme ends thereof, as and for the purpose set forth.

13. A throw-rail for combined third and traction rack rail switching systems, comprising a plate having perforations or openings therethrough arranged in lines or rows extending lengthwise thereof, and having transverse slots or openings intermediate the ends of such lines or rows of perforations and the end of such plate, said transverse slots or openings being of increasing length transverse of the plate in opposite directions from a central point, as and for the purpose set forth.

14. A throw-rail for combined third and traction rack rail switching systems, comprising a plate having perforations or openings therethrough arranged in lines or rows extending lengthwise of such plate, and having at one end transversely-extending slots or openings, and insulating flanking pieces

on opposite sides of such transverse slots, as and for the purpose set forth.

15. A throw-rail for combined third and traction rack rail switching systems, comprising a plate having perforations or openings therethrough arranged in lines extending lengthwise of said plate, such lines beginning near one end of such plate and crossing each other at a point near the opposite end of such plate, as and for the purpose set forth.

16. A throw-rail for combined third and traction rack rail switching systems, comprising a plate having perforations or openings arranged in lines extending in straight and curved lines extending lengthwise of said plate, said lines of perforations commencing at one end of such plate and meeting and crossing each other at a point near the opposite end of such plate and extending beyond said crossing-point and to the end of the plate, as and for the purpose set forth.

In witness whereof I have hereunto set my hand, this 12th day of April, 1904, in the presence of the subscribing witnesses.

JOHN H. MORGAN.
